(57) **CLAIM**

The ornamental design for a task chair, as shown and described.

DESCRIPTION

FIG. 1 is a perspective view of a task chair, looking toward the right front corner, showing my new design;

FIG. 2 is a front view thereof;

FIG. 3 is a right side view thereof;

FIG. 4 is a back view thereof;

FIG. 5 is a top view thereof; and,

FIG. 6 is a bottom view thereof.

The broken lines shown in the drawing are for illustrative purposes only and form no part of the claimed design.

The short even dashed lines shown on the seat, backrest, and armrests in all views are understood to represent stitching.
